METHOD AND APPARATUS FOR MAKING
BUILDING BLOCKS

Donald A. McKenzie, Milwaukee, Wis.

Application March 31, 1939, Serial No. 265,222

9 Claims. (Cl. 25—41)

This invention relates to building blocks and a method and apparatus for making the same.

The conventional so-called cored concrete building block, as is well known, comprises an oblong block having a number of large cored openings extending vertically therethrough. In laying-up a wall of blocks of this type, these cored openings align with each other so that the wall has continuous vertical passages. These unbroken passages permit air circulation, which is objectionable as it interferes with the intended insulating value of the air spaces.

In other words, the air spaces in a wall formed of such blocks are not strictly "dead" air spaces, and this invention, therefore, has as one of its objects to provide a building block of the type described having a higher insulating value due to the presence of definitely formed spaces, which are so constructed that when the block is incorporated in a wall, each individual space is closed at both ends so that it constitutes a dead air space in the strict sense of the word.

Another disadvantage of the conventional building block is that the surfaces to which the mortar is applied are really edges of relatively small area, which not only increases the cost of laying the blocks as it is more difficult to apply the mortar over a broken surface and much of the mortar is wasted, but the strength of the completed wall is limited by virtue of this edge to edge contact between the blocks, and the fact that the webs between adjacent openings are relatively narrow and unsupported.

With this in mind, the present invention has as another of its objects to provide a building block of greater strength due to a novel interlocking columnar formation, and one in which the surfaces to which the mortar is applied are either wholly unbroken or have only small regularly spaced openings which do not interfere with the application of the mortar, and which are closed by the mortar.

Another object of this invention is to provide a building block which is internally vibrated during its manufacture.

It is also an object of this invention to provide a new and improved manner of making building blocks wherein a plurality of vibrator cores serve the dual function of vibrating the block internally and producing cored openings which are either closed at both ends or open at one or both ends, but which are definitely closed at the time the block is incorporated in the wall.

Another object of this invention is to provide a practical and sturdy apparatus for internally

vibrating the plastic mass of which the building blocks are formed, which is so designed that the number of cored openings produced thereby may be readily altered.

Another object of this invention is to provide a building block having dead air spaces formed in the manner aforesaid, and which has a facing of natural stone.

In this respect, it is a further object of the invention to provide an improved method of making a building block having a natural stone facing which permits the use of drier concrete, or more specifically, a concrete having a more correct water ratio, without jeopardizing the strength of the bond between the facing and the concrete backing.

Another object of this invention is to provide an apparatus for making concrete building blocks which is so designed that the block during its formation can be subjected to internal and form vibration.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate several complete examples of the physical embodiment of the invention constructed in accordance with the best modes so far devised for the practical application of the principles thereof, and in which:

Figure 1 is a vertical sectional view through an apparatus constructed in accordance with this invention, and illustrating the manner in which the vibrating cores extend down into the plastic mass during the internal vibration;

Figure 2 is a view of the apparatus taken at right angles to Figure 1, and illustrating the vibrating cores lifted, and with the form prepared to receive the mass;

Figure 3 is a view similar to Figure 1, with the vibrating cores lowered as in Figure 1;

Figure 4 is a view similar to Figures 2 and 3, showing the vibrating cores lifted and the cored openings left in the concrete mass;

Figure 5 illustrates the manner in which the removal of excess concrete closes the open tops of the cored openings;

Figure 6 shows the form box lowered to expose the finished block;

Figure 7 illustrates a slight modification of the invention in which form vibration is utilized in conjunction with the internal vibration;

Figure 8 is a perspective view of a finished stone faced block;

Figure 9 is a detail view illustrating the construction of the vibrating cores;

Figure 10 is a perspective view of an all concrete block; and

Figure 11 is a plan view of the block shown in Figure 10, showing the arrangement of its dead air spaces in comparison to the arrangement of the cored openings of a conventional concrete building block.

Referring now particularly to the accompanying drawings in which like numerals indicate like parts throughout the several views, the numeral 5 represents a core box which is preferably arranged for vertical motion to and from an operative position coacting with a pallet 6 to form a receptacle for a mass 7 of concrete or other similar material.

It is desired to point out that where this specification and the claims refer to concrete, it is understood that the term is being used in its broad sense, and that all mixtures having a cementitious binder are included.

The form 5 may be arranged for vertical motion with relation to the pallet 6, as stated, or the pallet may be the movable part. The important thing is that relative vertical motion be provided between the form box and the pallet so that the finished block can be removed from the form.

In practicing this invention, it has been found expedient to provide a horizontally shiftable hopper 9 which slides over the open top of the form to facilitate depositing the plastic mass into it. This hopper, as shown in Figure 5, also acts to scrape off excess concrete after the block has been formed and vibrated, and in doing so, closes the open tops of the cored openings 10 left by the withdrawal of the vibrating cores 11.

The vibrating cores 11, as best illustrated in Figure 9, have a slight downward taper and are removably secured at their upper ends to a plate 12. A similar plate 13 held in spaced relation to the plate 12 at a distance beneath it and having holes 14 through which the vibrating cores pass serves to steady and reinforce the cores.

A simple manner of quickly detachably securing the individual cores to the plate 12 consists in the provision of a stud 15 secured in the upper end of the core and threaded to receive a clamping nut 16 which engages the top of the plate 12. In this manner, the number and arrangement of the cores may be quickly changed.

This flexibility is desirable for the reason that in some localities, the building codes require greater compressive strength than in other localities, and as it is desirable to have as many dead air spaces in the block as possible, the greatest number of cores compatible with the strength requisites is always used.

The plates 12 and 13 are secured to opposite ends of bushings 17 which are slidably mounted on vertical rods 18. These rods 18 are slideable in a stationary supporting frame 19. Above and beneath the bushings 17, the rods 18 have heavy coil springs 20 mounted thereon, and held in compression by collars 21 fixed to the rods.

Secured to the plates 12 and 13 and projecting up from the top plate are bearings 22 in which a shaft 23 is journaled. The shaft 23 is connected, through a flexible coupling 24, with a power shaft 25 driven by an electric motor 26.

The motor 26 and the bearings 21 for the shaft 25 are carried by a frame 28, which is rigidly secured to the vertical shafts 18. This frame is supported by cables 29 trained over sheaves mounted on the stationary support 19 and connected with a drum 30 also mounted thereon in such a manner that the entire vibrator structure may be quickly raised and lowered.

Vibration is obtained through the provision of two pairs of eccentric weights 31 adjustably secured to the shaft 23. In the construction illustrated, all of the weights are set to produce maximum vibration, and as will be readily apparent, the extent of vibration can be regulated by adjusting the relative positions of the eccentric weights on the shaft 23.

The description thus far describes in detail the method and apparatus employed in the manufacture of building blocks in accordance with this invention. To briefly summarize the method of procedure, the hopper is slid into position over the empty form box. Concrete is deposited in the form box. The vibrating cores are lowered into the plastic mass and vibrated for a period of approximately twenty seconds, which is long enough to give the mass sufficient rigidity to be self-supporting, and then while vibration is continued, the cores are withdrawn from the plastic mass. It is the continuance of the vibration together with the slight taper of the cores which permits them to be withdrawn from the mass, leaving the openings desired.

After the cores are fully withdrawn, the hopper is slid back across the core box or form, which scrapes off the excess material and automatically closes the open tops of the holes. Thereafter, the form is pushed down, leaving the finished block in position to be removed, as shown in Figure 6.

Where the block is wholly concrete, as illustrated in Figure 10, the method just outlined is followed. If it is desired to have the block provided with a natural stone facing, as shown in Figure 8, a stone slab 35 is set in the form box, as shown in Figure 2, before the concrete is deposited therein. This divides the form with the result that the finished unit is double and is left in this double formation until the blocks are about to be shipped to their place of use, when the slab is split flatwise in a manner shown and described in Patent No. 1,893,430 issued to D. A. McKenzie, January 3, 1933.

One advantage of the present invention is that it permits the use of a drier concrete, or rather one having a more correct water ratio without jeopardizing the bond between the stone facing and the concrete backing. This follows from the fact that during vibration, the water content of the concrete exudes outwardly toward the surfaces confining the mass, and thus provides the necessary moisture for the capillary action which brings about the bond between the stone facing and the concrete.

Where the apparatus is to be used for making stone faced blocks, as just described, it is only necessary to remove the center row of vibrating cores to accommodate the slab in the mold.

Another important advantage of the present invention is the fact that the multiplicity of vertical dead air spaces results in an interlocked columnar structure of great strength. This condition and its relationship to the conventional cored concrete block is illustrated in Figure 11. Attention is particularly directed to the fact that each of the columns formed by the separated air spaces has substantially the same cross

section, and that the large number of ties between the columns results in an exceptionally strong structure.

In the preferred embodiment of the invention, the dead air spaces are completely concealed by terminating the cored openings a distance above the bottom of the block, and by closing the open tops of the openings in the manner described. This produces imperforate top and bottom surfaces for the block, which is the optimum condition from the standpoint of mortar application.

It is obvious, however, that the advantages of this invention can be achieved with a construction in which the air spaces are left open at one or both ends, for the holes are sufficiently small that during mortar application, their presence is not objectionable for the reason that they are closed during the application of mortar so that the spaces are actually dead air spaces.

While internal vibration as described is generally sufficient, if desired, form vibration may also be employed, which may be accomplished in the manner illustrated in Figure 7. In this instance, the pallet 6 rests on a vibrating support 36 connected by means of a rod 37 with a shaft 38 having an eccentric weight 39 mounted thereon to produce the desired vibration.

From the foregoing description taken in connection with the accompanying drawings, it will be readily apparent that this invention provides an entirely new and improved building block having many advantages over building units heretofore in use.

What I claim as my invention is:

1. The herein-described method of making a building unit which consists in: depositing a mass of plastic material such as concrete in a mold cavity; inserting a multiplicity of slender vibrating cores into the plastic mass without bringing the cores into engagement with the supporting surfaces of the mold cavity; vibrating said cores until the mass has sufficient rigidity to be self-supporting; withdrawing the vibrating cores; and closing the open tops of the holes formed by the withdrawal of the cores.

2. The herein-described method of making a building unit which consists in: depositing a mass of plastic mixture such as concrete in a form; vibrating the mass internally until it has sufficient rigidity to be self-supporting by means of vibrating cores which extend into the interior of the mass from the top thereof but are spaced from the bottom of the mold; withdrawing the vibrating cores to leave a plurality of open topped holes in the unit, which holes are closed at their bottom; and closing the open tops of the holes to form wholly concealed dead air spaces in the unit and to render the top as well as the bottom surfaces of the unit imperforate.

3. The herein-described method of making a building unit which comprises: filling a form with a quantity of plastic mixture such as concrete in excess of the amount required to make the building unit; inserting a multiplicity of relatively slender vibrating cores having their axes parallel into the plastic mixture with a translating motion parallel to the axes of the cores and so that no part of the cores contacts the form; vibrating the cores until the mixture has sufficient rigidity to be self-supporting; with-

drawing the cores from the mixture with a translating motion parallel with the axes of the cores; wiping the excess plastic material from the top of the form which closes the open tops of the substantially small holes left by the withdrawal of the vibrating cores; and effecting relative motion between the bottom of the form and its sides to enable removal of the finished unit.

4. The herein-described method of making a building unit which consists in: placing a slab of natural stone in a mold; depositing a mass of cementitious material such as concrete in the mold alongside one face of the slab; and vibrating the mass internally while the mold is stationary to cause its moisture content to exude outwardly toward the surfaces contacting the mass to improve the bond between the stone and the mass.

5. The herein-described method of making a building unit which comprises: filling a form with a cementitious mixture such as concrete; internally vibrating the mixture by means of a multiplicity of slender vibrating cores which extend into the mass without contacting the form; and vibrating the form and consequently the mixture independently of the vibrating cores so that the conjoint action of the internal and external vibration to which the mixture is subjected quickly solidifies the mixture to the point of being self-supporting.

6. An apparatus for making building blocks and the like comprising: a form to hold a mass of plastic material such as concrete; a plurality of vibrating cores having their axes parallel; means supporting said cores for translating motion parallel with the axes of the cores into and out of the form and with no part thereof contacting the form in any position of the cores; resilient means mounting the cores on said support and isolating them from the support as to vibration; and means for vibrating the cores.

7. In an apparatus of the character described; a plurality of vibrating cores; a floating head carrying the cores; means for vibrating said head; and means for detachably securing the individual vibrating cores to the support so that the number of cores may be altered at will.

8. An apparatus of the character described comprising: a stationary support; a carriage suspended from the support; means on said support for raising and lowering the carriage; a plurality of depending vibrating cores; a vibrating head to which all of said vibrating cores are secured; resilient means connecting said head with the carriage; and means on the carriage for vibrating said head.

9. The herein-described method of making a building unit which comprises: forming a multiplicity of recesses in one face of a building unit during molding thereof by substantially parallel vibratory cores free of the walls of the mold inserted substantially through the body of the mass of which the unit is composed, said cores being of a size to form recesses of relatively small cross sectional area so that substantially the entire surface of said face is capable of supporting a bonding material such as mortar in the event the recesses are left open at said face of the unit.

DONALD A. MCKENZIE.
